[57] CLAIM

The ornamental design for a burial monument, as shown and described.

DESCRIPTION

FIG. 1 is a front elevational view of a burial monument showing our new design;

FIG. 2 is a rear elevational view of a burial monument of FIG. 1;

FIG. 3 is a left side elevational view of the burial monument of FIG. 1;

FIG. 4 is a right side elevational view of the burial monument of FIG. 1;

FIG. 5 is a top plan view of the burial monument of FIG. 1; and,

FIG. 6 is a bottom plan view of the burial monument of FIG. 1.

The broken line showing of the word logo in FIG. 1 is for illustrative purposes only and forms no part of the claimed design.
